CHIN SUPPORT FOR WASHBASINS

Filed April 3, 1930

UNITED STATES PATENT OFFICE

WILLIAM K. HOLCOMB, OF RIVERSIDE, CALIFORNIA

CHIN SUPPORT FOR WASHBASINS

Application filed April 3, 1930. Serial No. 441,348.

This invention relates to a device adapted to be attached to a wash basin to provide a chin rest for one having a head rinse after a shampoo or for any other operation which necessitates the holding of the head over the edge of a wash basin and constitutes a continuation in part of my application which was filed August 5, 1929 and bears the Serial No. 383,441.

10 The primary object of the present invention is to provide a light, attractive device which may be easily and quickly applied to a wash-stand basin to provide a chin support as above described.

15 Another object of the invention is to provide a device which may be kept clean and sanitary and which is so formed that it will not interfere in any respect with the carrying out of other operations at the wash basin.

20 The invention will be best understood from a consideration of the following detailed description taken in connection with the accompanying drawing forming part of this specification, with the understanding, however, that 25 the invention is not confined to any strict conformity with the showing of the drawing but may be changed or modified so long as such changes or modifications mark no material departure from the salient features of 30 the invention as expressed in the appended claims.

In the drawing:

Figure 1 is a view in front elevation of the chin rest.

35 Figure 2 is a view in top plan of the same.

Figure 3 is a view in transverse section of the chin rest and a portion of a wash basin to which it is shown applied.

40 Referring more particularly to the drawing wherein like numerals of reference indicate corresponding parts throughout the several views, the numeral 1 indicates generally a wash basin or bowl of the type which is normally mounted upon a suitable pedestal (not shown), the basin proper being usually surrounded by a ledge 2 which is bordered by a depending surrounding panel or skirt 3.

45 The device embodying the present invention is shown applied to the basin and as shown it comprises an elongated plate 4 pref-

erably of light metal such as aluminum, along one edge of which is formed a depending panel 5 which, as shown, is formed integral therewith thus making the plate of substantially L-shaped cross-section.

55 The plate 4 is pressed to provide a depression 6 therein for the reception of the chin of a user of the device, this depression, as shown, being of arcuate contour and opening along the upper edge of the plate 4 opposite the 60 edge along which the panel 5 is formed so that when the device is in place upon a wash basin in the manner shown the open side of the chin rest 6 will discharge into the basin any water which may flow thereinto.

65 At each end of the plate 4 has a bowl edge engaging bracket which is indicated generally by the numeral 7. Each of these brackets is preferably formed of a single band of material preferably the same as that of which the plate 4 is formed, this band being shaped to provide a depending front arm portion 8 which, at its upper end, passes across the inner face of the panel 5 and continues from there diagonally across the corner formed 70 between the panel and the plate 4 providing the brace bracket 9, the upper end of which is secured to the plate 4 by a rivet or other suitable means as indicated at 10. From the point where the band is attached to the plate 4 by means of the rivet 10 as shown it continues inwardly and downwardly forming the arcuate arm 11 which is designed to overlie the inner face of the basin or bowl 1 and this 75 is bent back or returned in the form of the basin contacting portion 12 which terminates at the rear of the panel 5 to which it is secured by a rivet or other suitable securing means 13

80 which passes through the panel and the interposed upper end of the front arm 8. The basin contacting portion 12 of each of the bracket bands passes through a rubber casing 14 which prevents the marring of the enamelled surface of the basin 1 by the band. The 85 free end of the arm 8 of each bracket is adapted to be bent under the lower edge of the skirt 3 of the basin in the manner shown and indicated at 15 after the arm portion 11 and the adjacent rubber covered portion 12 has been 90

95 100

positioned over the inner face of the bowl or basin in the manner shown.

From this it will be readily seen that by the provision of the two arms 8 and 11 at each end of the plate 4 the same will be firmly held in position over the edge of the basin and when the device is used in a hair dressing establishment or similar place of business the patron will be provided with the firm support for his head when the same is being washed instead of having to rest his chin against the edge of the basin or support it in a strained position over the edge of the basin.

15 Having thus described my invention, what I claim is:

1. A wash basin attachment of the character described, comprising a plate having a chin receiving depression formed therein inwardly of one edge thereof and extending to an adjacent parallel edge, and a bracket carried thereby and adapted to grip the edge of the wash basin to maintain the body in position thereon, with said plate having the said adjacent edge directed inwardly of the basin to drain thereinto.

2. A wash basin attachment of the character described, comprising a plate formed to provide a chin receiving depression, a supporting bracket at each end of the plate comprising a pair of arms, one designed to engage over the outer portion of the bowl and the other being adapted to extend into the bowl for engagement with the inner surface thereof, and an apron formed along one edge of the plate for extension over the front of the bowl.

3. A wash basin attachment of the character described, comprising an elongated plate having a chin receiving depression therein and opening through one longitudinal edge thereof and a right angularly disposed apron portion extending along the opposite longitudinal edge, and a bowl gripping bracket at each end of the plate for supporting the same over an edge of the wash basin, comprising a band like metal body secured intermediate its ends to the under surface of the plate and to said apron and formed at each side of the point of connection with the plate and apron to provide a pair of bowl engaging arms, one thereof being normally vertically disposed for engagement across the outer face of the bowl, the other of the arms extending inwardly and downwardly from the plate for engagement with the inner surface of the bowl.

4. A wash basin attachment of the character described, comprising an elongated plate having a chin receiving depression therein and opening through one longitudinal edge thereof, a bowl gripping bracket at each end of the plate for supporting the same over an edge of the wash basin, comprising a band like metal body secured intermediate its ends

to the under surface of the plate and formed at each side of the point of connection with the plate to provide a pair of bowl engaging arms, one thereof being normally vertically disposed for engagement across the outer face of the bowl, the other of the arms extending inwardly and downwardly from the plate for engagement with the inner surface of the bowl, each of said other arms being continued to form a return bent portion terminating at the upper end of the adjacent outer arm and secured thereto, and a protecting body encasing each of said return bent portions.

5. A wash basin attachment of the character described, comprising an elongated plate having a chin receiving depression formed therein intermediate its ends and opening through one longitudinal edge thereof, a panel formed at right angles to the plate along the other longitudinal edge thereof, and a wash basin engaging bracket attached to the plate and the panel at each end and comprising a one piece band like body secured intermediate its ends to the plate and to the panel, that portion of the band lying between the points of attachment to the plate and the panel constituting a brace, the portions of the band at opposite sides of the points of connection with the chin rest being formed to provide inner and outer bowl engaging arms, the outer arm being normally disposed substantially vertically, the inner arm extending inwardly and downwardly and being continued to form a return bent portion adapted to contact with the inner face of the basin.

In testimony whereof I hereunto affix my signature.

WILLIAM K. HOLCOMB.
